[57] CLAIM

The ornamental design for a hunter's removable cap cover with license holder attachment, as shown and described.

DESCRIPTION

FIG. 1 is a front elevational view of the hunter's removable cap cover with license holder attachment showing my new design;

FIG. 2 is a rear elevational view thereof;

FIG. 3 is a right side view thereof;

FIG. 4 is a left side view thereof;

FIG. 5 is a top plan view thereof; and,

FIG. 6 is a bottom plan view thereof, the opening is conventional.
